UNITED STATES PATENT OFFICE

149,813

DESIGN FOR A RING BOX

Morton Hollis, Brookline, Mass., assignor to Axel Bros., Long Island City, N. Y., a corporation of New York

Application May 20, 1947, Serial No. 139,150

Term of patent 3½ years

(Cl. D80—5)

To all whom it may concern:

Be it known that I, Morton Hollis, a citizen of the United States and a resident of Brookline, in the county of Norfolk and Commonwealth of Massachusetts, have invented a new, original, and ornamental Design for a Ring Box, of which the following is a specification, reference being had to the accompanying drawing, forming a part thereof, in which the figure is a view in perspective of a ring box, showing my new design.

The sides of the ring box which are not shown are unornamented.

I claim:

The ornamental design for a ring box, substantially as shown and described.

MORTON HOLLIS.
